UNITED STATES PATENT OFFICE.

RICHARD F. DOWNEY, OF MILWAUKEE, WISCONSIN, ASSIGNOR, BY MESNE ASSIGNMENTS,
TO OTTO R. BARNETT, OF CHICAGO, ILLINOIS.

ANTICREEPING DEVICE FOR RAILS.

No. 902,567.

Specification of Letters Patent.

Patented Nov. 3, 1908.

Application filed February 11, 1907, Serial No. 356,700. Renewed October 7, 1907. Serial No. 396,327.

To all whom it may concern:

Be it known that I, RICHARD F. DOWNEY, a citizen of the United States, and resident of Milwaukee, in the county of Milwaukee and State of Wisconsin, have invented certain new and useful Improvements in Anti-creeping Devices for Rails; and I do hereby declare that the following is a full, clear, and exact description thereof.

10 The invention consists in certain peculiarities of construction and combination of parts as hereinafter described with reference to the accompanying drawings and subsequently claimed, its object being to provide simple, 15 economical and effective means for the prevention of rail-creeping.

In the drawings: Figure 1 represents a cross-section of a portion of a railway rail with an anti-creeping rail-bracket embodying the features of my invention in position thereon; Fig. 2, a similar view showing the bracket in position to be adjusted to the rail; Fig. 3, an elevation of the same in position on a rail, with parts broken away and parts in 25 section to better illustrate the details, and Fig. 4, a detached plan view of said bracket.

Referring by letter to the drawings, A indicates a rail-flange having secured thereto a metallic bracket B. The body-portion of 30 the bracket consists of a strap having a hook-end C, which end grips one edge of the rail-flange, while an upturned nose D at the opposite end of said bracket serves to grip the adjacent rail-flange edge. The bracket has a depending wing E, that abuts against the side of the tie and thereby prevents the rail from 35 creeping.

In practice, the distance between the throat of the hook C and inner face of the nose D is 40 slightly less than the width between edges of the rail-flange. In order to fit the bracket to a rail-flange, it is first subjected to heat sufficient to expand the same, the bracket being then applied by means of suitable tongs. The 45 hook-end is first adjusted to one end of the rail-flange (as shown in Fig. 2) and the nose thereafter pressed over the opposite edge. By the above method the bracket, when cooled, will be firmly shrunk upon the rail in 50 the desired position, and consequently after cooling becomes practically a part of said rail, the result of which is an absolute check against slipping of the bracket upon said rail when the latter is subjected to a creeping 55 strain.

The above described arrangement dispenses with all bolts, etc., which are common to this class of device, and thereby not only greatly reduces the cost in manufacture, but also saves time in adjusting the anti-creepers, thus providing a single clamping member that will accomplish the desired result, which heretofore required three or more separate parts.

If desired, when the heated bracket is first 65 affixed to the rail, its nose may be slightly struck over the edge of the rail, by a hammer-blow, in order to make the contact more perfect, and while I have shown one form of bracket, it is understood that it is within the 70 scope of my invention to vary the same indefinitely, the essential feature consisting of a metallic clamping-member adapted to be subjected to heat and thereafter shrunk upon a rail for the purpose specified.

While, for efficient holding power, I consider that the clamping member ought to be shrunk upon the base flange of the rail by the use of heat as above described, it may well be that under some conditions it may be 75 sufficiently shrunk, clamped or gripped upon the rail by a mere bending of the ends of the clamp over the rail flange under sufficient pressure. It is obvious that whether the clamp is sufficiently contracted upon the rail 80 flange by heating and cooling, or by heating, applying bending pressure and then cooling, or by simply applying sufficient bending pressure upon the clamping ends of the devices are matters relating merely to 85 the manner of assembling the parts, the assembled combination broadly embodying my invention and being essentially the same 90 whichever procedure is followed.

I claim:

1. An anti rail-creeping device adapted to be shrunk upon a rail.

2. An anti rail-creeping device comprising a single member adapted to be shrunk upon a rail-flange.

3. An anti rail-creeping device having rail-flange engaging-ends, the distance between the ends being normally of less dimension than the width of the rail-flange, and adapted to be shrunk on said rail-flange.

4. An anti rail-creeping device comprising a body-portion having upturned ends, and a depending flange extending from the body-portion, said device being adapted to be shrunk upon a rail-flange.

110

5. The combination with a railroad rail, of an anti-creeping device shrunk thereon.
6. The combination with a railroad rail, of an anti-creeping device shrunk thereon and provided with a shoulder arranged to engage a relatively stationary abutment to prevent creeping of the rails.
7. The combination with a rail, of a one-piece anti-creeping device secured to the rail by having its opposite ends arranged to grip the opposite edges of the base flange of the rail so as to be secured thereto against movement in all directions, said anti-creeping device being provided with means for engaging an abutment to prevent creeping of the rail.
8. A one-piece anti-creep provided with ends adapted to be caused to directly grip the opposite edges of the rail base so as to be secured thereto against movement in all

directions and with a depending wing or shoulder adapted to engage an abutment to prevent creeping of the rail.

9. An anti-creeping device comprising a member, the integral ends of which are constructed and arranged to be contracted upon opposite edges of a rail flange so as to be secured thereto against movement in all directions, and means on said member for engaging an abutment to prevent creeping of the rail.

In testimony that I claim the foregoing I have hereunto set my hand at Milwaukee in the county of Milwaukee and State of Wisconsin in the presence of two witnesses.

RICHARD E. DOWNEY.
